UNITED STATES PATENT OFFICE.

CHARLES E. FARRINGTON, OF CALDWELL, NEW JERSEY.

CHAIR.

SPECIFICATION forming part of Letters Patent No. 628,306, dated July 4, 1899.

Application filed March 17, 1899. Serial No. 709,387. (No model.)

To all whom it may concern:

Be it known that I, CHARLES E. FARRINGTON, a citizen of the United States, residing at Caldwell, in the county of Essex and State of New Jersey, have invented certain new and useful Improvements in Chairs; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

The objects of this invention are to provide a chair, more particularly for children, which can be readily and quickly folded into a small space, so as to be packed within a trunk, valise, or the like and transported from place to place, to enable the device to be securely and easily fastened to some other article of furniture, such as an ordinary dining-room chair, and thus form a "high chair," as commonly called, which can be placed in position before the dining-table, and to secure other advantages and results, some of which may be referred to hereinafter in connection with the description of the working parts.

The invention consists in the improved folding chair and in the arrangements and combinations of parts of the same, all substantially as will be hereinafter set forth and finally embraced in the clauses of the claim.

Referring to the accompanying drawings, in which like letters and figures of reference indicate corresponding parts in each of the several views, Figure 1 is a side elevation of the folding chair. Fig. 2 is a perspective view of a clamp by means of which the said folding chair is attached to the said other article of furniture. Fig. 3 is a front elevation of the said folding chair. Fig. 4 is a plan of a tray preferably employed with said folding chair. Fig. 5 is an edge view of the same. Fig. 6 is a front view of the chair folded. Fig. 7 is a front view of the seat and back with the arms and uprights removed. Fig. 8 is a plan of the seat and back, the side supports for the seat and arms being in horizontal section. Fig. 9 is a detail showing a portion of the

arm and upright in side elevation. Fig. 10 is a sectional view taken at line *x*, Fig. 9; and Fig. 11 is a detail view of a portion of the seat.

In said drawings, *a* indicates a dining-room chair or other article of furniture to which my improved folding chair may be applied, and *b b* are standards for the folding chair, which are preferably curved downwardly outward from the other portions of the said chair, and have at their lower extremities clamps *c*, by means of which the said standards may be securely fastened upon the said chair *a*. The said clamps are of a peculiar construction, whereby they may be made at a small cost and yet be effective in securely attaching the folding chair to any article of furniture.

The clamp *c* is attached to the lower end of the standards by means of eyebolts *d d*, *e*, and *f*, (shown more clearly in Fig. 2,) the eyebolts *d d* being inserted in the standards closely near the lower end thereof at the opposite sides, the bolt *e* being arranged at about midway between the opposite edges of the standards suitably above the eyebolts *d d*, and the eyebolt *f* being arranged vertically beneath the eyebolt *e* in a horizontal plane and a little above the horizontal plane of the eyebolts *d d*.

Within the eyes of the bolts *e f* is arranged a thumb-screw *g*, and on said thumb-screw is arranged a threaded nut or casting *h*, the opposite arms of which are provided with eyes *h'* to receive the downwardly-projecting or hooked ends *i* of a wire clamping-frame *j*. The said wire clamping-frame is of peculiar construction and comprises a piece of heavy wire which is bent double in a horizontal plane to engage the bottom of the chair or article of furniture, as at *j'*.

From the horizontal portion of the clamp-frame the arms *j' j'* of said frame extend upward through the eyes *d d* and are bent at their upper ends inward and downward to engage the nut *h* and enter in the eyes *h'* thereof, and thus it will be noticed that by turning the thumb-screw *g* in its eyebolt the said nut *h* will be raised or lowered upon said bolt and with it the frame, so that the said frame will be brought into clamping relation with

the chair *a*, whose edge enters between the horizontal portion *j* of the clamp and the lower extremity of the standard.

The manner in which the standards *b* are connected at their upper parts to the body of the folding chair, and which will be hereinafter more fully described, admits of a limited movement of the lower extremities of the standards toward or apart from each other, 10 whereby the folding chair may be attached to other articles of furniture of different widths.

The standards *b* are each in sections *b*' *b*², the section *b*² at the upper extremity of a standard being rigidly secured to one of the 15 arms *k* of the folding chair, the arm and upper section of the standard forming a T-shaped construction. The said upper sections are hinged to the lower section, as indicated in Fig. 1, the hinge-pin of the hinge 1 and the joints 20 formed between the upper and lower sections being formed and arranged at angles other than right angles, whereby in the folding operations the lower sections will lie side by side substantially parallel with one another and 25 will not interfere with one another in the folding operations, as will be hereinafter more fully described.

To hold the upper and lower sections in alinement, I employ a catch of peculiar construction, consisting of a wire piece *m*, bent double or into a U shape, the upper extremities of which are bent over the upper end of the upper section *b*², the doubled lower part of the wire *m* forming an open tongue adapted 30 to extend around a lip *n*, secured to the inside of each of the lower sections. When the upper section *b*² of the standard is inserted in the arm of the chair, the said ends of the wire piece *m* are inserted therewith and are thus 35 held firmly in place, so that the said doubled wire lies securely against the inward face of the upper section and projects below the joint formed between the two sections into engagement with the lip *n*, above referred to. Thus 40 when the lip *n* and double wire *m* are in engagement it will be evident that the sections *b*' and *b*² will be prevented from turning on the hinge-pin above referred to, and the sections will be locked in their desired positions 45 of alinement. When it is desired to fold the sections in the operation of folding the chair, the doubled wires *m* are thrown inwardly away from the lips *n* by means of pushing-pins *o*, which extend through the lower sections *b*', 50 and at the outer sides of said sections are provided with heads *o*' to receive the thumb in the pushing operation. By pushing on the said heads *o*' the doubled portions of the wires *m* are thrown away from the lips *n*, so that 55 the upper sections can be turned on the hinge-pins to permit the desired folding, as will be understood.

Below the hinged joints of the standards the latter are adapted to enter into apertures 60 formed in the opposite edges of the seat *r* of the folding chair, said apertures being of a size to properly receive the standards and ef-

fect a nice fitting of parts. At the rear edge of the seat *r* the same is provided with eye-bolts *r*², which extend upward from said seat 70 and lie against the sides of certain downwardly-projecting portions of the back *s* of the folding chair, and screws *s*' are inserted through said eyes into said downwardly-projecting portions, as shown in Figs. 3 and 7, 75 the said screws serving as hinge-pins, by means of which the back may be folded down upon the upper face of the seat.

The seat *r* of the chair is held upon the standards *b* by means of wires *p*. (Shown 80 more clearly in Figs. 1, 8, and 9, where the said wires are shown to be pivoted to the under side of the arms in eyebolts *p*' *p*', holding said wire up against the under sides of said arms.) The lower extremities of the said 85 wires *p* are hooked or provided with eyes and enter eyebolts *r*³, secured in the upper side of the seat near the opposite edges thereof. The said wires *p* thus hold the seat in suspensory relation to the arms of the chair and yet permit of the independent folding of the arms 90 with relation to said seat in the manner hereinafter described.

By means of the standards *b* being fitted into the recesses *r*' in the opposite edges of 95 the seat the said seat is kept in proper horizontal position with firmness and without much strain upon the other parts above described.

The rear extremities of the arms *k* of the 100 chair are provided with screws *q*, which project backward from said rear extremities, and between the rear extremities of the arms and the heads of the screws are adapted to enter sockets or recesses *u* of peculiar formation 105 at the opposite lateral edges of the back *s* of the chair, the said sockets being shown more clearly in Fig. 7 of the drawings. The said recesses *u* are preferably of a hooked shape, the inner end lying above the horizontal plane 110 of the mouth of the recess for the purposes hereinafter more particularly described in connection with the operation of folding. Said recess *u* is at its upper part, in which the screw lies when the arm is in position for use, 115 considerably wider than the diameter of the engaging screw, thereby permitting a lateral movement of the arms and enabling the lower ends of the standards to be spread apart or brought nearer together in fitting the chair to 120 supports of various widths, said standards swinging pivotally upon their fastening to the edges of the seat as a fulcrum.

The standards *b* are firmly held in the recesses *r*', formed at the opposite edges of the 125 seat, by means of locking-tongues *v*, which are pivoted on the seat and extend around the outsides of the standards, and at their free ends are adapted to enter into engagement with catches *v*² on the seat, the said 130 catches being preferably screw-heads, over which the resilient extremity of the locking-tongue may be sprung. I prefer to employ two or more of the said catches or screw-heads

v^2 , by means of which I am enabled to accommodate the standards to the seats of chairs of various widths. The said tongues at their free extremities are preferably turned upward, as at v' , to provide finger extensions, by means of which the operation of the said tongues is facilitated.

The seat r of the chair is preferably made double, the central portion of the upper thickness w forming the ordinary chair-seat and the lower thickness w' enabling the device to be used as a child's commode. To this end the central portion g of the upper thickness is hinged at its rear edge and adapted to be tipped up out of the way, and the lower thickness of the seat is provided with a large central opening t' , the ordinary chair or other article of furniture upon which the folding chair is fixed being adapted to support a suitable receptacle beneath said central opening w'' , as will be understood without further description. For greater convenience I prefer to make a rectangular portion t of the lower thickness of the seat, as shown in Fig. 11, removable, the said removable portion containing the opening t' .

To hold the child within the chair and provide the usual rest or shelf in front of him, I employ a tray which is attachable to the forward extremities of the arms k . The said tray is provided at each side within the raised margin g and above the horizontal board 4 thereof with a wire 5 , which is bent at right angles, one extremity entering the raised margin g and the other arm or extension passing downward through the bottom of said tray, the said wires being suitably riveted in place and forming horizontal slots into which screws 6 , secured at the forward extremities of the arms k , extend. The heads of the screws prevent the wires 5 from drawing off in the forward direction, and the shank of said screw serves as a bearing for the wire to prevent downward movement. The tray is thus supported on said screws 6 , and the weight of the forwardly-projecting part causes the floor of the tray back of the wires 5 to lie against the under sides of the arms k , whereby the tray is firmly held in proper position.

The raised rim g is discontinued at proper points near the ends of the rear edge of the tray to allow the floor to come flat against the arm k , as will be understood.

At the rear edge of the tray beneath the arms of the folding chair I employ springs 7 , adapted to engage screws 8 , projecting downward from the under side of the arms. The said springs are fastened to the rear edge of the tray, near the opposite ends thereof, and are arranged edgewise, so that the rear flat side of said spring will come into engagement with the shank of the screw 8 and lie above the head thereof. The lower edge of the spring will then engage the head of the screw, and thus when the parts are in proper rela-

tive position the tray will be held in the desired horizontal position against an uplifting of the front edge. When desired, however, the said tray can be readily detached from the arms of the chair by simply drawing the free extremities of the springs away from the shanks of the depending screws.

In operating the device I first remove the tray from the chair and afterward arrange it on the under side of the seat when packing the parts away. I next release the tongues v , by means of which the standards b are held in the recesses r' at the opposite sides of the seat, turning the said tongues on their pivots so that the handled extremities v' of said tongues lie against the rear screw-bolts r^3 . The standards are then free to be withdrawn downwardly outward from the sides of the seat with the arms, and as this is done the screws q at the rear extremities of the arms k are withdrawn from the recesses u at the opposite edges of the back. This operation frees the said back, so that the same may be turned forward on its hinges and brought to lie flat upon the seat. I then turn the arms k and the upper sections b^2 of the standards attached thereto, so that they lie upon the upper or back surface of the back of the chair, and then turn the lower sections b' of the standards inwardly on the hinges 1 , so that they overlie the arms.

Thus in the folded conditions shown in Fig. 6 I have first the seat, then above the seat the back, then above the back the arms, and then above the arms the lower sections of the standards, with their clamps, all folded so that the chair is brought into a very small compass and can be packed away in a trunk and occupy but comparatively little space therein.

It is evident that should I desire to do so the folding chair may be clamped to a simple flat frame or board 10 , as shown in Fig. 3, instead of to an ordinary chair, and be used as a low chair instead of a high chair.

The parts thus described are most of them of simple construction, and the combination is easily understood by the operator and permits of very quick operation in folding and unfolding. The result is a child's chair admirably adapted to several uses, easily carried about and capable of being readily connected to any ordinary chair in position for use.

Various changes and modifications may be made from the exact construction described without departing from the spirit and scope of the invention, and I do not wish to be limited by the positive descriptive terms employed, except as the state of the art may require.

Having thus described the invention, what I claim as new is—

1. The improved folding chair herein described, in which is combined a seat, a back and arms pivotally connected with said seat and hinged standards connected to said arms, and extending therefrom below the seat at their lower ends having clamping-jaws, all

said parts being adapted to fold flatwise together, substantially as set forth.

2. The improved chair herein described, comprising a seat, a back and arms pivotally connected with said seat and adapted to fold together thereon, and standards connected to said arms and separably held against the sides of said seat, and clamps at the bottoms of said standards, adapted to engage the edges of a dining-room-chair seat or the like, substantially as set forth.

3. The improved folding chair herein described, comprising a seat, back and side arms hinged thereto and standards fixed to said arms and extending downward through recesses in the edges of the seat, means for holding said standards in said recesses, and said standards being hinged between said seat and arms, said back, arms and standards being adapted to all fold flatwise together upon the seat, substantially as set forth.

4. In a folding chair, the combination of a seat, a back hinged thereto, arms, wires pivotally secured to both said seat and an arm, standards connected at their upper ends to said arms and projecting below said seat and thereat being provided with means for attachment to a support for said chair, and means for holding the standards to the edges of the seat and permitting the projecting lower ends to be spread more or less, substantially as set forth.

5. A folding chair comprising a seat recessed at its opposite lateral edges, a back, arms adapted to engage said back, wires pivotally connected to said arms and seat, and jointed standards fixed at their upper ends to said arms and extending down through said recesses in the seat and having clamps at their lower ends, and an adjustable clasp securing said standards in said recesses, substantially as set forth.

6. In a chair of the character described, the combination with the seat and back, the latter having outwardly-opening recesses or slots curving upward, of arms pivotally connected to said seat and having their rear ends adapted to be brought into said recesses, said recesses being at the inner end considerably wider than the engaging ends of the arms and allowing a lateral adjustment thereof, substantially as set forth.

7. The combination in a folding chair having a seat, and arms and back hinged thereto, of standards fixed at their upper ends to said arms and extending downward past the seat, each of said standards being joined between the arm and seat to form upper and lower sections, a lip projecting from the lower section and a spring-tongue lying against the upper section and extending downward to engage

said lip and hold the joint against action, substantially as set forth.

8. In a folding chair, the combination with a seat, folding back and arms, of jointed standards extending downward from said arms, means for temporarily securing said standards against the edges of the seat and means for holding said joints against bending, substantially as set forth.

9. The combination with a chair having standards, of clamps each comprising a doubled wire portion having a vertical part sliding in bearings projecting from the standard, its upper ends bent inward and secured to a nut interiorly threaded, and its lower end bent inward at substantially right angles and underlying the bottom of the standard, and a threaded bolt extending through said nut and turning in bearings on the standards, substantially as set forth.

10. In a child's chair, the combination with the side arms having screws or hooks forwardly projecting from the forward extremities of said arms, of a tray having a plane board floor or bottom, wire loops or staples projecting upward from said floor near the rear edges and adapted to hook onto said screws at the forward extremities of the arms when the front edge of the tray is elevated, said tray normally lying with that portion of its bottom at the rear of said wire loops or staples in contact with the under surface of the arms, substantially as set forth.

11. The herein-described child's chair, in which is combined a seat and a back, the latter having outwardly-opening curved or hooked slots or recesses for the arms, arms separably connected to said back and pivotally connected to said seat whereby said arms can be swung outward from engagement with the back and also folded inward upon the other parts, substantially as set forth.

12. The combination in a child's chair, of a seat, a back hinged to said seat and having hook-shaped projections at the outer lateral edges, and arms pivotally connected to said seat and being adapted to engage at their rearward ends or extremities said projections, the hooked walls of said projections holding the said arms against horizontally outward or lateral movement, and said rear ends or extremities of the arms having heads or enlargements preventing forward withdrawal, substantially as set forth.

In testimony that I claim the foregoing I have hereunto set my hand this 28th day of February, 1899.

CHARLES E. FARRINGTON.
